UNITED STATES PATENT OFFICE.

ARTHUR H. GUSTAFSON, OF JERSEY CITY, NEW JERSEY, ASSIGNOR TO HENRY E. HOLBROOK, OF BOSTON, MASSACHUSETTS.

MACHINE FOR SEALING CIRCULARS.

Application filed June 9, 1920. Serial No. 387,573.

To all whom it may concern:

Be it known that ARTHUR H. GUSTAFSON, a citizen of the United States, and resident of Jersey City, Hudson County, State of New Jersey, formerly of Chicago, Cook County, Illinois, has invented an Improvement in Machines for Sealing Circulars, of which the following description, in connection with the accompanying drawing, is a specification, like characters on the drawings representing like parts.

This invention pertains to sealing or wafer applying machines adapted particularly for applying wafers or stamps to folded sheet material for mailing or other purposes.

The particular embodiment of my invention described herein is illustrated in the accompanying drawings in which:

Fig. 1 is a plan;

20 Fig. 2, a side elevation partly broken away;

Fig. 3, a vertical longitudinal section on the line 3—3, Fig. 1, also partly broken away;

25 Fig. 4, a partial vertical detail looking at the ratchet wheels 74, 75, from the right, Fig. 2.

Fig. 5, a partial side elevation similar to Fig. 2, with a bracket 25 broken away for 30 clearness to show more in detail the article controlled step by step wafer feeding means; and

Fig. 6, a partial vertical section of the step by step feeding means on the line of the rib 35 29, Fig. 2.

My novel sealing machine comprises, Figs. 1, 2, 3, a base 1, with suitable supports or legs 2, and a table 3 supported above the base as by feet 4, along which the folders or sheets are fed from the Fig. 1, right hand end.

For feeding the sheets I have provided the following novel construction. On the base 1, Fig. 1, and preferably near the forward end, is mounted a suitable motor 5 adapted to be connected by a wire 6 with any convenient source of power, as an ordinary electric light socket, not shown, and controlled by a switch 7.

This motor Fig. 1, carries a worm shaft 8, shown in dotted lines in mesh with a gear 9, similarly shown, on a shaft 10 extended across the machine base and suitably journaled therein.

The shaft 10 carries herein two sprocket

wheels 11, over which run sprocket chains 12, which travel through two slots or channels 13 on the table 3, to similar sprocket wheels 14 at the rear end of the table, mounted on a shaft 15, see dotted lines, Fig. 1. This shaft 15 is journaled in the frame or 55 base 1 and carries at one end Fig. 1, a gear 16 in mesh with a smaller pinion 17, dotted lines, on the end of a folder accelerating shaft 18 supported at its opposite end in an arm 19 on the base 1. This shaft carries a 60 plurality of accelerating rollers 20, as of rubber and, as they are geared to run faster than the sprocket wheels 14 and gear 16, they accelerate the initial speed of the folder and position it quickly upon the table ready to 65 be fed forward by the first lugs 21 on the chains 12 to approach it after it is positioned.

By this novel means the operator is relieved of the necessity of depositing the 70 folders on the table 3 each time just ahead of the lugs 21 which requires very close watch of the chains and accurate feeding of the folders, and which is very fatiguing.

Even if the folders are deposited late for 75 the set of approaching lugs, the rollers 20 pick up the folders and push them ahead on the table in advance of the lugs, ready to be fed forward by them to the wafer or stamp applying elements.

80 In the table top and properly located is a wafer or stamp receiving or holding pocket 23 which will be hereafter referred to.

The stamp magazine, and feeding and applying mechanism are carried by a head 24, 85 Figs. 1, 2, 3, supported on and connecting opposite bracket members 25 supported, in turn, from the two sides of the base. One of the brackets is hinged at 26 so that by removing the screws 27 the head and brackets 90 may be raised to allow access to the parts not otherwise readily accessible.

The head 24 comprises two upright side members 29, 30, Figs. 1, 2, having flanges 31, which are secured to the brackets 25, 26, by 95 screws 32. Depending from the brackets and, herein, at either side of said head, are two pressure bars 33 which are suspended by means of pins 34 with adjustable heads 35 thereon, the pins carrying spiral springs 100 seated against the members 33 and the under faces of the brackets 25.

These members 33 serve to keep the fold-

ers flat on the table 3 and prevent them from overriding the lugs 21 on the chains 12, the adjustment of the members 33 being made to accommodate the particular folder in use 5 if necessary.

Mounted between the sides 29, 30, Figs. 2, 3, and near the top of the same, is the wafer or stamp magazine 37. This magazine is shown as a hollow or tubular member in this 10 case, although it obviously may be of any shape in cross section to receive the particular outline of stamp to be used.

The bottom 38 of the magazine, Fig. 3, is preferably inclined somewhat and partly 15 cut away to permit the wafers to impinge upon the transferring member to be described, at the proper angle.

The wafer 39 Fig. 3, may be pressed downward by a weight 40 and this, in turn, may 20 also have additional pressure applied to it as desired by a coiled spring 41 seated against the weight and top 42 of the magazine 37 and encircling the rod 43 threaded into the weight and extended through the 25 top 42 and carrying a knob 44 by means of which the weight may be withdrawn against the pressure of the spring when the magazine is to be filled.

Secured to the front and lower end of 30 the magazine Fig. 3, is a wafer pressure finger and guide 45 which acts to retain the wafer closely against the wafer picking roll and guide it to the further transferring members, all to be described.

35 The transfer or wafer picking roll 46, Fig. 3, is mounted on a shaft 47 journaled in the sides 29, 30, and is provided with a wafer feeding surface of rough rubber or similar material that will impinge upon and pick 40 off the bottom wafer from the stack in the magazine and carry it forward beneath the wafer guiding finger 45.

Just in advance of the roll 46 are a series 45 of smaller feeding or transferring rolls 48 also having a wafer feeding surface as of rubber or other suitable material all journaled in the side members 29, 30.

In the rear of the rolls 48, Fig. 3, and beneath the picking roll 46 is the transferring 50 and moistening roll 49 of similar construction, the roll being kept moist by the wick 50 protruding forward and against the roll from the water reservoir 51. This reservoir may be filled through an opening 52 at its 55 top and is supported by slots 53 on its sides which receive ribs 54, see dotted lines Fig. 3, on the inner edges of the bracket ends 23, thus permitting ready withdrawal of the reservoir when desired.

60 On the Fig. 1, upper end of the shaft 47 is a gear 55 which meshes with a small gear 57 on the shaft of top roll 48, and this roll is in turn so connected with the remaining rolls 48, by means of geared idlers 58 just 65 in advance of them, that the rolls 48 all ro-

tate in the same direction and the roll 46 cooperates therewith to receive the wafer from the magazine and feed it downward.

To strip the wafer or stamp from the roll 46, Figs. 1, 3, and ensure the feeding of the 70 same to the folder, I provide two wafer stripping needles 59 which are mounted on a bar 60 pivotally secured between the sides 29, 30. The upper ends of these needles are curved to rest in grooves 61 in the face of 75 the roll 46, and thus they underlie the wafer as it is fed forward by the roll and guide 45 to the point where it is impinged by the rolls 48, and then fed downward against the 80 moistening roll 49 from whence it drops into the pocket 23 already referred to in an upright position under the guidance of the needles 59.

I have found that the wafer or stamp is more effectually applied to the folder by 85 first, a combined rubbing or smoothing action, and second, by a direct or perpendicularly applied pressing action. Hence I have provided novel means for obtaining this result. To that end, Fig. 1, I secure to inwardly extended flanges 62 on the inner faces of the sides 29, 30, and at the forward end of the same, a plate 63. Depending 90 from this plate by means of pins 64 to which it is threaded, Fig. 3, is a smoothing plate 95 65, frictionally adjustable heads, as of rubber, 66 on the pins 64 serving to suspend the plate at the proper distance.

Springs 67, Fig. 3, on the pins provide the 100 necessary pressure, for the plate 65, for smoothing out the wrinkles in the wafer and laying it smoothly on the opposite sides of the folder.

In advance of the smoothing plate 65 are the pressure rolls 68, 69. The former is 105 mounted, Fig. 1, in two elongated bearings 70 which are secured to the forward end of the plate 63. The bearings are drilled vertically to receive each a spring pressed pin 71, Fig. 3, the spring 72 being seated against 110 the pin and against a screw 73 threaded into the top of bearing. The roll 69 is journaled in the table 3. These rolls may be of any desired material.

For actuating the picking roll 46 with a 115 step by step motion to ensure regular and positive feeding of the wafers, I provide the shaft 47 on the Fig. 1 lower end, with a ratchet wheel 74 with the teeth pointed rearwardly of the machine, and beside it a 120 ratchet wheel 75 with the teeth pointed forwardly of the machine, both wheels fast on the shaft.

Depending from the shaft 47, Fig. 2, is an 125 arm 76, with a hub 77 fast thereon, which arm drops through a slot or cut away portion 78 of the table 3 into the path of the advancing folder. The upwardly extended arm 79, on the hub Fig. 4, has its end offset 130 and it overlies the ratchet 74, said offset end

carrying a pawl 80 which, by a spring 81, Fig 2, is kept in engagement with the teeth of the ratchet 74.

The arm 79 is provided with a spring 82 which is coiled about the hub 77 and then carried rearwardly and secured to the side 29, the spring acting thus to normally throw the arm 79 and its pawl 80 forward to feed the ratchet 74 and roll 46 forward to the extent of the throw.

Pivottally secured also to the side 29 just in the rear of and below the ratchet 75, Fig. 2, is a horizontal lever 83, see also Figs. 5, 6, the forward end of which is bent laterally, Fig. 6, to bring it beneath the teeth of the ratchet 75. The lever end is also provided with a tooth 84, Fig. 6, which, when the arm 79 is in its Fig. 2 upright position, engages the teeth of the ratchet 75 and prevents forward or anticlockwise motion of the ratchet and shaft 47.

Extended upwardly from the lever 83 is a finger 85 which, when the ratchet 75 is at rest, lies close behind the arm 76 and thus holds the tooth 84 on the lever 83 in engagement with the ratchet 75 locking the latter. But when the arm 76 is swung forward out of the path of the finger 85 by the contact therewith of the article to be sealed, the finger 85, and tooth 84 on the lever 83 under the influence of a spring 86 secured to the side 29 and bearing against the lever 83 is depressed, thus releasing the ratchet 75 and shaft for rotation one step.

The arm 76 will be held in forward or stamp feeding position by the contact with the lower end thereof of the article until the article has passed beyond the end of the arm, and then it will be returned to normal position, Fig. 2, by the spring 82.

Thus I have provided an article controlled stamp feeding means and, being article controlled, it is variable at will as to speed or frequency of feeding the stamp. Obviously as the arm 76 is not released until the article has passed its lower end, the arm 76 cannot rotate the roll 46 again to feed forward another stamp until it is released, whether the folder be wide or narrow.

A counter 90, Fig. 1, of any approved type may be mounted on the bracket 25 so that it will be actuated by the travelling folders. In this case the counter has a depending arm 87 which is raised sufficiently by each passing folder to actuate the recording mechanism.

The operation of the machine is as follows:

Folders 88 are fed by the operator beneath the accelerating rolls 20 and by them drawn quickly forward so that they will be engaged by the first pair of lugs on the chain.

The lugs carry the folder forward beneath the picking roll 46 and as the folder passes beneath the roll its forward edge, Fig. 2, engages the lever arm 76 and pushes it for-

ward and raises it sufficiently to permit the folder to pass. The previous rotations of the roll 46 have picked a series of wafers from the magazine 23 and fed them forward about the roll 46 guided by the finger 45 and the transferring rolls 48 and moistening roll 49 and needle 59, and the leading wafer 87a has been positioned edgewise, Fig. 3, in the pocket 23. The forward folder edge engages the wafer which yields, and is carried forward, the lower half being laid against the lower face of the folder by the curved edge 89 of the pocket 23. The upper half of the wafer is laid down upon the folder by the curved edge 90 of the smoothing plate 65. As the folders are fed forward by the chains the plate 65 and table 3 smooth out all the wrinkles in the wafer and draw the opposite halves tightly against the edge of the folder to close the edges securely. As the wafer passes between the rolls 68, 69, it is pressed firmly against the opposite sides of the folder and caused to adhere securely thereto.

The feeding of the wafers is timed by proper proportioning of the length of the lever arm 76, and the size of the teeth on the ratchets 74, 75.

As the arm 76 is swung forward by the folder the finger 85 swings forward therewith and permits the tooth 84 to drop from engagement with the ratchet 75 thereby permitting the said ratchet and ratchet 74, when the arm 76 is feeding the folder, to rotate clockwise to the extent permitted by the swinging arm 76.

During the swinging of the lever 76 forward, a pawl 89 pivoted to the side 29 engages the ratchet 74 and prevents it from rotating clockwise also. When the arm 76 is allowed by the folder to drop back to normal position it raises finger 85 and tooth 84 so that the latter engages the ratchet 75 and prevents it from rotating backward or anticlockwise.

My invention is not limited to the particular embodiment herein described and illustrated, but its scope is rather to be determined by the appended claims.

Claims:

1. In a machine of the class described, folder accelerating means for quickly feeding a folder to folder feeding means, means for feeding a folder, article controlled step by step wafer transferring means for carrying a wafer to the path of the folder, wafer holding means, wafer smoothing means, and wafer pressing means.

2. In a machine of the class described, folder feeding means, article controlled step by step wafer transferring means comprising a wafer picking roll, a wafer stripper and wafer feeding rolls cooperating therewith to carry the wafer to the path of the folder, a picking roll feeding lever actuated

by the folder for rotating the roll, and wafer smoothing means:

3. In a machine of the class described, means for feeding a folder, article controlled step by step wafer transferring means for carrying a wafer to the path of the folder and comprising a wafer picking roll, a wafer stripper and wafer feeding roll cooperating therewith, a wafer smoothing pressure plate, and a wafer pressing roll for applying the wafer to the folder.

4. In a machine of the class described, means for feeding a folder, article controlled step by step wafer transferring means for carrying a wafer to the path of the folder and comprising a wafer picking roll, a wafer guiding pressure finger therefor, a wafer stripper and wafer feeding rolls cooperating therewith, a wafer smoothing pressure member, for applying the wafer to the folder.

5. In a machine of the class described, means for feeding a folder or the like, a wafer magazine, article controlled step by step means for carrying a wafer to the folder, means for stripping a wafer from the carrying means, wafer positioning means for placing a wafer loosely across the plane of travel of the folder or the like, and means for folding the wafer across the edge of the folder as the latter continues its travel including wafer smoothing means and wafer pressing means.

6. In a machine of the class described, means for moving folders or the like through the machine, means for accelerating the initial movements of the folders, a magazine for wafers, an article controlled friction wafer picking roll adapted to successively pick wafers from the magazine, and transferring rolls cooperating with the picking roll to transfer the wafer to the path of the folder.

7. In a machine of the class described, a belt for advancing folders or the like successively through the machine, means for accelerating part of the movement of the folders, article controlled step by step wafer transferring means including a wafer picking roll for carrying the wafers to the path of the folder, means for stripping the wafers from the wafer picking roll, and means for placing the wafer in cooperating relation with the folder.

8. In a machine of the class described, means for advancing folders at a non-uniform speed through the machine, article controlled step by step wafer supplying means comprising a wafer picking roll, and wafer feeding rolls cooperating therewith for transferring a wafer from a remote point to the plane of the folder, means for stripping a wafer from the wafer picking roll, wafer smoothing means and a wafer pressing means for drawing the opposite facing of

the wafer closely against the edge and opposite faces of the folder.

9. In a machine of the class described, means for moving a folder or the like through the machine at a non-uniform speed, a wafer magazine, article controlled step by step wafer transferring means for carrying the wafer successively from the magazine including a wafer picking roll, means to strip the wafer from the picking roll, and means to receive the wafer from the stripping means and position it to be received by the folder.

10. In a machine of the class described, comprising the table 3, folded conveyors 11, 12 thereon, means for actuating the same, the head 24 with the wafer magazine 37, the wafer guide 45 and wafer pressing member 41 on the head, folder pressure bars 33 on the table, wafer picking member 46 rotatably mounted in the head and operatively positioned relative to the magazine 37; wafer feeding rolls 48 and moistening roll 49 in the path of travel of the wafer, pocket 23 in the table and wafer stripping member 59 for stripping the wafer from the roll 46 and guiding the same to the pocket, wafer smoothing member 65 and pressure means 64, 67 therefor; wafer pressing members 68, 69 and resilient member 72 for the same, and article controlled step by step wafer feeding means for the roll 46, comprising a ratchet member 74 operatively connected with the roll 46, swinging arm 76, 79 and pawl 81 thereon movably connected with the ratchet 74 and adapted to be actuated by the moving article to impart step by step movement to the roll 46.

11. In a machine of the class described comprising wafer applying means, means for feeding a folder toward the wafer applying means, step by step wafer transferring means variable as to speed for transferring wafers to the folder, and wafer smoothing means to act on the wafer and folder to effect the adhesion of the former to the latter.

12. In a machine of the class described, an endless conveyer for feeding the folders through the machine, a wafer magazine, a wafer picking roll arranged to pick a wafer from the bottom of the magazine, and a wick fed moistening roll positioned to receive the wafer from the picking roll and feed it across the path of the folder.

13. In a machine of the class described, an endless conveyer for feeding the folders through the machine, a wafer magazine, wafer carrying rolls, a wafer picking roll positioned to pick the wafers from the magazine in a plane substantially parallel with the path of the folder, wafer stripping members for stripping the wafer from the picking roll and presenting it to the carry-

ing rolls, one of which is a wick fed moistening roll.

14. In a machine of the class described, an endless conveyer for feeding the folders through the machine, a wafer magazine, a wafer picking roll engaging the wafers tangentially, a wafer guiding finger to guide the wafer across the path of the folder, wafer carrying rolls, including a wick fed

moistening roll between the wafer picking roll and the path of the folder, and wafer smoothing means for smoothing the wafer on opposite faces of the folder in a direction opposite to the direction of travel of the folder.

In testimony whereof, I have signed my name to this specification.

ARTHUR H. GUSTAFSON.
